Primary Examiner — Jeffrey D Asch*(74) Attorney, Agent, or Firm* — Morgan, Lewis & Bockius LLP(57) **CLAIM**

The ornamental design for a mobile phone, as shown and described.

DESCRIPTION

FIG. 1 is a front perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The broken lines, which are immediately adjacent to the shaded areas and define unshaded regions, represent the bounds of the claimed design. The broken lines and the non-shaded regions within the broken lines form no part of the claimed design. The unevenly broken line at the rear of the top input jack in FIG. 8 is a contour line.
